UNITED STATES PATENT OFFICE

HENRY G. GEOFFRAY, OF CLEVELAND, OHIO

WALL STRUCTURE AND ATTACHMENT

Application filed September 12, 1927. Serial No. 219,013.

This invention relates to building construction, and more particularly to wall structures carrying radiators, wash-basins, sinks, or other plumbing fixtures, etc.; and it is among the objects of the invention to provide a construction which as incorporated in a wall is inconspicuous and which permits of safely carrying the weight. Other objects and advantages will appear as the description proceeds.

To the accomplishment of the foregoing and related ends, the invention, then, consists of the features hereinafter fully described, and particularly pointed out in the claims, the following description and the annexed drawing setting forth in detail certain structure embodying the invention, such being illustrative however of but a few of the various forms in which the principle of the invention may be employed.

In said annexed drawing:—

Fig. 1 is a fragmentary sectional view of a wall showing an embodiment of my invention; Fig. 2 is a view in perspective showing the wall-members in dis-assembled relation and in slightly modified form; Fig. 3 is a perspective view showing the inclusion of a face plate; Fig. 4 is a perspective view of the back of the plate; Fig. 5 is a perspective view of the bracket member; and Fig. 6 is a similar view of a modified form.

Referring more particularly to the drawing, there is shown a wall W, between the bricks or hollow tile 2 of which is embedded an anchor having a hook 3, a horizontal or wall-engaging arm 4, and a vertical or anterior arm 5. Preferably the same members may be accommodatable to engage over one or more brick or hollow tile as advisable in any particular circumstances, and where such a range is desired, the arm 4 instead of being formed as an integral member will preferably be extensible, with telescoping sections 4a, 4b. The latter may be integral with the arm 5, or secured to it, as by an angle-piece 6. Bolts 7 or screws, the one member being tapped and threaded, may then be used to secure the sections together. Advantageously, the telescoping sections may be arranged in tongue and groove relation, a groove 8 co-

acting with the tongue or ridge 9, whereby additional lateral rigidity may be had if desired. In order to facilitate the proper extension in accordance with the number of brick to be bridged, a series of bolt holes 10 may be arranged in the mating members, such that the securing-bolts 7 may find aligning holes as extended to the position desired. While in some instances, the hook 3 may be integral with the section 4a, usually it is more advantageous as a separate member, the series of bolt holes thus facilitating still further adjustability. Coactable with the anterior arm 5 are interchangeable attachment-carriers, these varying somewhat in their form, depending upon the particular load to be carried, whether a radiator for instance, or a sink, or other fixture. For radiator suspension, a bracket-like member 11 having a holding notch 12 may be bolted or screwed directly to the anterior plate 5. By providing a back strip 13 as a part of the bracket, and arranging screw heads 14 therein, seating of the bracket may be readily and quickly had by engagement in one or more of a series of key-hole-like openings 15 in the anterior arm. That is, the bracket may be seated by inserting the screwhead or screwheads 14 into the enlarged portion of the opening and thence sliding downwardly into the slotted portion. Instead of a thickened back piece 13 into which the screws may be tapped or bolts may be entered, I contemplate in some instances forming the bracket 11a, Fig. 6, with a lateral flange or a series of lateral lugs 16 which may be tapped and threaded to receive screws or merely tapped to receive bolts, as may be desired. For the carrying of sinks, wash basins, etc., an attachment-carrier in the form of a face plate 17 is advantageous. Such face plate may be secured to the anterior arm by screws or bolts, or preferably a screw or screws 18 may be set into the back of the member, such as to engage in the keyhole-like openings 15 at the height required, the plate being secured by placing it against the arm such that the screw-heads projecting from the rear of the plate align with and enter the enlarged portion of the selected keyhole openings and then with a slight downward move-

ment the screw-heads lock by the narrow portion of the openings.

It will be understood that the wall-engaging arm 4 is placed as the wall is being built up. Otherwise, more or less digging out and relaying of bricks will be required. And with the anterior member positioned against the laid up wall, the appropriate attachment-carrier is secured in place on the anterior arm 5. In the case of a radiator carrier or the like 11, the wall is plastered, the plastering then covering the anterior arm 5 and the base of the attachment-carrier. The radiator or the like can then be hung without any interfering with the mounting. In the case of a sink, wash stand or other fixture, the face plate 17 is applied as the attachment-carrier, being secured to the anterior arm 5. When the wall is now plastered, the plaster line will come just flush with the face of the member 17, and will cover the anterior arm 5. Only the face member 17 will thus be visible, and in mounting the plumbing fixture, securing screws or bolts therefor may take into the plate 17 at the appropriate point, a series of holes 19 having been provided in the plate, so as to allow for ample positioning vertically or laterally. In some instances also, for special fixtures, this allows further of drilling and tapping in situ as may be required. Where a finish facing of marble or glazed tiling is to be applied, the wall structure is set as foregoing, and finally the marble is set in position, an opening being left however, over the face plate 17, such that this is exposed back of the thickness of the marble. The face plate is thus available for the attachment of fixtures as desired, while the anterior arm 5 is entirely concealed.

It will thus be seen that a versatility of mounting may be had as regards spacing, whether in the wall itself, or as to the vertical or lateral placement of the fixture carried. At the same time also the entire construction is as rigid as the wall itself, and since the major portion is covered in, there are no unsightly members visible. Where desired, an expansion-bolt or the like 20 may also be set through the anterior arm 5 into the wall.

Other modes of applying the principle of the invention may be employed, change being made as regards the details disclosed, provided the means stated in any of the following claims or the equivalent of such, be employed.

I therefore particularly point out and distinctly claim as my invention:—

1. A universal wall-carried support, comprising an extensible arm adapted to be laid up in a wall, means permitting extending said arm, said means comprising telescoping sections having rib and groove interengagement, an anterior arm connected to the first-

mentioned arm, an attachment-carrier engageable with said anterior arm, and means for regulating the height of said attachment-carrier relative to said anterior arm.

2. A universal wall-carried support, comprising an extensible arm adapted to be laid up in a wall, means permitting extending said arm, said means including telescoping sections, an anterior arm connected to the first-mentioned arm, and an attachment member having groove and rib engagement with said anterior arm, and means for regulating the height of said member relative to said anterior arm.

Signed by me this 9th day of September, 1927.

HENRY G. GEOFFRAY.
